W. L. CHURCH

SPEAR

Filed Oct. 12, 1923

UNITED STATES PATENT OFFICE.

WALTER L. CHURCH, OF HOUSTON, TEXAS, ASSIGNOR OF ONE-HALF TO L. M. PEARCE,
OF HARRIS COUNTY, TEXAS.

SPEAR.

Application filed October 12, 1923. Serial No. 668,101.

To all whom it may concern:

Be it known that I, WALTER L. CHURCH, a citizen of the United States, residing at Houston, in the county of Harris and State 5 of Texas, have invented certain new and useful Improvements in a Spear, of which the following is a specification.

This invention relates to new and useful improvements in a spear.

10 One object of the invention is to provide a tool of the character described which has been specially designed for the purpose of being let down into a well bore to engage with the pipe which may be stuck therein 15 and by means of which the stuck pipe may be recovered.

Another object of the invention resides in the provision of a tool of the character described which may be readily released from 20 the pipe and withdrawn in case the pipe is so tightly stuck that it cannot be withdrawn.

A further feature of the invention resides in the provision of a spear of the character 25 described which is of very simple construction, which may be cheaply and easily manufactured, and readily kept in repair and which is very effective in accomplishing the purposes intended.

30 With the above and other objects in view, the invention has particular relation to certain novel features of construction, operation and arrangement of parts, an example of which is given in this specification, and 35 illustrated in the accompanying drawings, wherein:

Figure 1 shows a side view of the spear.

Figure 2 shows a vertical, sectional view.

40 Figure 3 shows a transverse sectional view taken on the line 3-3 of Figure 2; and,

Figure 4 shows a transverse sectional view taken on the line 4-4 of Figure 2.

45 Referring now more particularly to the drawings, wherein like numerals of reference designate similar parts in each of the figures, the numeral 1 designates a cylindrical mandrel to the upper end of which there is threaded a long coupling 2, whose upper end is internally threaded to receive the lower end of the stem or string of pipe 3, by means of which the tool is handled in letting the same down into the stuck pipe, and in withdrawing the same. The lower end of the mandrel is enlarged form-

ing a head 4 whose lower end is rounded off or tapered, as at 5 to facilitate its entrance into the pipe. On opposite sides the head has the downwardly diverging flat faces, or ways 6, 6, formed with the central grooves 7, 7, dove tailed in cross section, and slideable on these respective faces or ways, are the pipe engaging jaws 8, 8, which, in general contour, are tapered downwardly or wedge shaped. The outer faces of these jaws are arcuate to conform to the shape of the pipe to be pulled and are provided with the teeth 9 to engage with said pipe, and the inner sides of the jaws have the lengthwise ribs 10, 10, to fit into the grooves 7. The lower ends of said grooves are flared as at 11, so as to facilitate the insertion of the jaws on the flared faces 6. The upper ends of the faces 5, terminate at the abrupt shoulders 12 of the head, which shoulders form stops to limit the upward movement of said jaws, and above the respective jaws the head has the oppositely disposed vertical grooves, 13, 13.

80 Slidably mounted on the mandrel above the head 4, there is a long collar 14 whose lower end is formed with the oppositely disposed downward extensions 15, 15, adapted at times to rest upon the upper end of the hand and formed to fit downwardly through the grooves 13, and contact against the upper ends of said jaws to expand them as hereinafter explained.

85 The sleeve 14 has the outwardly curved flexible friction members 16, 16, secured thereto. These friction members are preferably of the form of flat springs which are fastened rigidly at their upper ends to the collar 14. The lower ends of these ribs have vertical slots as 17 and set screws, as 18, pass through said slots and are threaded into the collar 14, so as to form a slideable anchorage of the lower ends of the friction members 16 to said collar.

90 As before stated the mandrel is cylindrical and it has a central water course 19 extending through it from end to end. There is a comparatively light tubular rod 20 within the mandrel whose upper end projects up into the collar 2, and has a washer 21, secured thereon by means of a nut 22, and interposed between this washer and the upper end of the mandrel and surrounding the rod 20, there is a comparatively strong coil spring 23. Beneath the 100

shoulders 12 the head has a comparatively wide keyway 24 therethrough and a long key 25 is anchored to the lower end of the rod 20 and works in said keyway, and the 5 respective ends of said key are fitted into bearings 26, 26, cut transversely through the jaws 8, said jaws having a sliding fit on the respective ends of the key. This key is not of sufficient thickness to block the 10 water passageway through the rod 20.

The operation of the device is as follows:—When the tool is to be let down into the bore, the mandrel is turned in such position relative to the collar 14 that the extension 15 will rest upon the upper end 27 of the head. The pressure of the spring 23 will then be effective to operate through the rod 20 and the key 25, to hold the jaws 6 elevated against the shoulders 12, and they 20 will be then in withdrawn or non pipe-engaging position. The tool is then let down into the bore and enters the pipe therein, and the friction members 16 will frictionally engage with said pipe sufficiently to 25 hold the sleeve 14 against turning while manipulating the tool, but the friction will not be sufficient to prevent the upward or downward movement of the tool. When it is desired to engage the tool with the pipe, the 30 stem 3 is given a partial turn, turning the mandrel with it, until the extensions 15 strikes the stops 28, 28, and are stopped in such position that the grooves 15 are 35 aligned underneath the extensions 13, and an upward pull then exerted through the stem causes the lower ends of the extensions 15 to contact against the upper ends of the jaws 8 causing a relative downward movement of said jaws on the faces 6, and these 40 faces being flared will cause said jaws to move outwardly or expand into engagement with the pipe, and they will grip and hold the pipe so that a further upward pull on the stem 3 will in many cases dislodge the 45 pipe so that it may be withdrawn.

If the pipe cannot be pulled and it is desired to release the tool and withdraw it, the stem 3 is lowered so as to unseat the extensions 15 from the grooves 13, and is then 50 partly turned to bring said extensions and grooves out of alignment and thereupon the expansion of the spring 23 will withdraw the jaws 8 into upper position, as shown in Figure 2, thus causing them to also move inwardly to release the pipe and tool may then be readily withdrawn from the bore.

What I claim is:

1. A pipe engaging spear including a support, a head carried by the support and having vertical side grooves and inclined por-

tions beneath said grooves, jaws mounted to slide on said inclined portions, yieldable means sustained by the support and connected to and supporting said jaws, a sleeve on said support above said head whose lower 65 end is formed with projections adapted to work through said grooves.

2. A pipe engaging spear including a support, a head carried by the support and having vertical side grooves and inclined portions beneath said grooves, jaws mounted to slide on said inclined portions, yieldable means sustained by the support and connected to and supporting said jaws, a sleeve on said support above said head whose lower 75 end is formed with projections adapted to work through said grooves, and external friction means on said sleeve.

3. A pipe engaging spear including a support, a head carried by the support and having vertical guides and inclined portions beneath the guides, jaws mounted to slide on said inclined portions, yieldable means sustained by the support and connected to and supporting said jaws, a member mounted on said support above the head, projections carried by the lower end of said member and adapted to work through said guides.

4. A pipe engaging spear including a support, a head carried by the support and having vertical guides and inclined portions beneath the guides, jaws mounted to slide on said inclined portions, yieldable means sustained by the support and connected to and supporting said jaws, a member mounted on said support above the head, projections carried by the lower end of said member and adapted to work through said 90 guides and external friction means on said member.

5. A pipe engaging spear including a support, a head carried by the support and having vertical guides and inclined portions beneath the guides, jaws mounted to slide on said inclined portions, yieldable means sustained by the support and connected to and supporting said jaws, a member mounted on said support above the head, projections carried by the lower end of said member and adapted to work through said 95 guides, said spear having a water course extending from its upper to its lower end.

In testimony whereof I have signed my name to this specification in the presence of 115 two subscribing witnesses.

WALTER L. CHURCH.
